(57) **CLAIM**

The ornamental design for a cherry separator as shown and described.

DESCRIPTION

FIG. 1 is a top perspective view of a cherry separator showing the claimed design;

FIG. 2 is a bottom perspective view thereof;

FIG. 3 is a front elevational view thereof;

FIG. 4 is a rear elevational view thereof;

FIG. 5 is a left side view thereof; FIG. 6 is a right side view thereof;

FIG. 7 is a top plan view thereof;

FIG. 8 is a bottom plan view thereof;

FIG. 9 is an exploded bottom perspective view of the cherry separator; and,

FIG. 10 is an enlarged detail view of portion 10 shown in FIG. 9.

The dashed broken lines show portions of the cherry separator that form no part of the claimed design. The dot-dash broken lines illustrate the border of the enlarged detail views and form no part of the claimed design.
